UNITED STATES PATENT OFFICE.

OSCAR B. LINTNER, OF POTWIN, KANSAS.

SHEARS.

1,081,974.

Specification of Letters Patent. Patented Dec. 23, 1913.

Application filed June 4, 1913. Serial No. 771,641.

To all whom it may concern:

Be it known that I, OSCAR B. LINTNER, a citizen of the United States, residing at Potwin, in the county of Butler and State 5 of Kansas, have invented certain new and useful Improvements in Shears; and I do hereby declare the following to be a full, clear, and exact description of the invention, such as will enable others skilled in the art 10 to which it appertains to make and use the same.

This invention relates to shears provided with pivoted cutters and operated by compound levers; and it consists in the novel 15 construction and combination of the parts hereinafter fully described and claimed.

In the drawings, Figure 1 is a side view of a shears constructed according to this invention. Fig. 2 is a plan view of the same.

20 The machine is provided with a supporting base 2, and 3 and 4 are two uprights secured to the base. These two uprights are similar to each other, and each is formed of two side plates having a guide channel 25 5 between them, and the upright 3 has a curved extension 6 at its top which forms a guide for the pivoted blade. The pivoted blade 7 is pivoted to the top of the upright 4 and projects through the guide channel 30 of the upright 3.

A stationary blade 8 is secured horizontally between the upper parts of the uprights 3 and 4 in any approved manner, and is arranged in operative relation to the 35 pivoted blade.

A lever 10 is pivoted by a pin 11 in the guide channel of the upright 3, and one end of the lever 10 is pivotally connected with the free end of the blade 7 by a link 12 and 40 pins 13. The other end portion of the lever 10 is provided with a forked jaw 14 which is arranged at an angle to its main portion. A lever 15 is pivoted at one end to a lug 16 on the upright 3, below the stationary

blade, by means of a pin 17, and the other 45 end portion of the lever 15 works in the guide channel of the upright 4. The middle part of the lever 15 has a longitudinal slot 18, and 19 is a pin which slides in the slot 18 and connects the forked jaw with the 50 lever 15.

A handle 20 is provided and has a curved lower end portion 21 which is pivoted by a pin 22 to the end of the lever 15 which projects through the upright 4. The handle is 55 pivoted to the upper part of a rocker-arm 24, which is pivoted to the base by a bracket 25 and a pin 26, and this rocker-arm forms a movable fulcrum for the handle. The pivoted blade is shown in its raised position 60 in Fig. 1, and when the handle is moved to the left, it operates the compound levers, and the pivoted blade descends and cuts off any object inserted between the blades.

What I claim is:

65 In a shears, the combination, with two uprights, and a stationary blade secured between them; of a blade pivoted to one of the uprights, a lever pivoted to the other upright and having a forked jaw at one end 70 arranged at an angle to its main portion and provided with a pin, a link pivotally connecting the free end portion of the pivoted blade with the adjacent end portion of the said lever, a second lever pivoted to the last 75 said upright above the pivot of the said lever and having a longitudinal slot at its middle part which engages with the said pin, a handle pivoted to the free end portion of the second lever, and a pivoted rocker-arm 80 which supports the said handle and forms a movable fulcrum for it.

In testimony whereof I have affixed my signature in the presence of two witnesses.

OSCAR B. LINTNER.
